UNITED STATES PATENT OFFICE.

ROBERT M. STEPHENS AND JAMES H. HOLLAND, OF CARROLLTON,
GEORGIA.

SWITCH-OPERATING MECHANISM.

No. 797,467.

Specification of Letters Patent.

Patented Aug. 15, 1905.

Application filed April 28, 1905. Serial No. 257,933.

To all whom it may concern:

Be it known that we, ROBERT M. STEPHENS and JAMES H. HOLLAND, citizens of the United States, residing at Carrollton, in the county of Carroll and State of Georgia, have invented new and useful Improvements in Switch-Operating Mechanism, of which the following is a specification.

This invention relates to certain new and useful improvements in switch - operating mechanism, and has for its object to provide novel mechanism operatively associated with the switch-points combined with devices carried by the car for operating said mechanism at will.

In order that the invention may be clearly understood, we have illustrated the same in the accompanying drawings, in which—

Figure 1 is a plan view of a section of a track provided with our improved switch-actuating apparatus. Fig. 2 is a longitudinal section on the line 2 2 of Fig. 2; and Fig. 3 is a sectional detail view of the forward portion of a car, showing in elevation one of the devices for operating the switch-actuating levers.

Referring to the drawings, 1 indicates the rails of the main line, and 2 the rails of the switch, said rails being supported upon the ordinary cross-ties 3, as usual.

4 indicates the switch-point, which is pivotally connected at 5 to the switch-rail 2 in the usual manner.

Pivotally mounted on the under side of a cross-tie 5^a, located adjacent to the switch-point 4, is a bell-crank lever 6, having a long arm 7 pivotally connected at its outer end to a rod 8, which in turn is pivotally connected to the switch-point 4. The pivot for the bell-crank lever is indicated at 9, one end of said pivot being suitably mounted in the cross-tie and the other end in the metal plate 10, secured on the under side of said cross-tie, the latter being suitably recessed, as indicated by 11, to provide a housing for said lever.

12 13 indicate, respectively, throw-levers which are pivotally mounted at one end in the outer ends of the arms 14 of the bell-crank lever.

15 16 indicate, respectively, trip - levers which are pivotally mounted on a bar 17, supported in blocks 18, extending between two of the ties or in any other manner that may be preferred. Each of the trip-levers is bifurcated at its lower end, as indicated at 19,

and the throw-lever 12 is pivotally mounted at its other end in the bifurcated portion of the trip-lever 15. The throw-lever 12 is similarly pivotally connected with the trip-lever 16. As will be clearly apparent, a moving body engaging either one of the trip-levers 15 or 16 will operate to turn the bell-crank lever on its pivot 9, and thus cause the switch-point to move toward or from the rail 1, depending upon which of the trip-levers is operated and the direction in which the body is moving. This operation of the trip-levers is preferably caused by the devices illustrated in Fig. 3, only one of which is shown in detail, however. Referring to this figure, 20 indicates a square pin which passes through and works in a correspondingly-shaped aperture formed in the car-platform 21 and also toward its lower end in a housing 22, having a squared opening for receiving said pin and suspended from the bottom of the platform by means of bolts 23 engaging ears 24 on opposite sides of said housing. A brace-rod 25, bolted at one end to an ear 26 on the bottom of said housing and at its other end to the car body or platform, suitably braces the housing 22. A coil-spring 26^a is interposed between the housing 22 and a collar 27, secured on the pin 20 and located on the under side of the platform, said collar serving, as will be understood, to limit the upward movement of the pin 20. A similar collar 28, secured on the pin 20 above the platform, limits the downward movement of said pin. 29 indicates a cap or head secured on the upper end of the pin 20 and affording a sufficiently broad bearing-surface for the foot of the motorman. The lower end of the pin 20 is bifurcated, as indicated at 30, and in this bifurcated portion is rotatably mounted a wheel 31. The pin 20 is mounted at one side of the platform 21, and a similar pin 20 is mounted at the other side of said platform.

In operation as the car approaches the switch the motorman will depress one or the other of the pins 20, and thus bring the roller 31 in position to come in contact with one or the other of the trip-levers 15 16, according to the movement it is desired to impart to the switch-point 4. Of course as one of the trip-levers is depressed by the roller 31 the other trip-lever will be elevated. Each car will be provided at both ends with the actuating-pins 20, so that switches can be operated by a car

moving in either direction. In the construction illustrated it will of course be apparent that the switch mechanism is one operated by a car traveling from left to right of the drawings, the car traveling in the other direction operating the switch-point, if the latter be closed, by the flange of its wheel, as usual. If the switch-point be in the proper position to cause the car to take the desired direction, neither of the pins 20 is depressed and the rollers 31 pass the trip-levers without engaging them.

Having thus fully described our invention, what we claim as new, and desire to secure by Letters Patent, is—

1. A switch-operating device comprising in combination with a pivoted switch-point, a bell-crank lever pivotally mounted in relation thereto, a rod pivotally connecting said switch to one arm of said bell-crank lever, a pair of upright trip-levers pivotally mounted intermediate their ends side by side adjacent to said bell-crank lever and normally projecting above the track, a pair of throw-levers connected at opposite ends, respectively, to the other arms of said bell-crank lever and to the lower ends of said trip-levers, and depressible

means comprising a pair of spring-controlled pins carried by a car for actuating one or the other of said trip-levers.

2. Switch-operating mechanism comprising in combination with a pivoted switch-point and means for moving the same, comprising a pair of upright trip-levers pivotally mounted intermediate their ends and normally projecting above the track, devices carried by a car for actuating one or the other of said trip-levers, each of said devices comprising a housing mounted below the car-platform, a pin mounted and adapted to work in said housing and having its upper end extending through and projecting above the car-platform, a collar secured on said pin below the car-platform, a coiled spring interposed between said collar and said housing, and a roller mounted in the lower end of said pin.

In testimony whereof we have hereunto set our hands in presence of two subscribing witnesses.

ROBERT M. STEPHENS.
JAMES H. HOLLAND.
